SNUBBER FOR DIPPER DOOR ON
POWER SHOVELS

Lewis W. Edwards, Lancaster, Pa., and Gerald
Von Stroh, Huntington, W. Va., assignors to
Lukens Steel Company, Coatesville, Pa., a cor-
poration of Pennsylvania

Application June 10, 1949, Serial No. 88,376

9 Claims. (Cl. 214—146)

1

This invention relates to new and useful improvements in snubbing or damping devices, and relates more particularly to devices for snubbing or damping free swinging movement of hinged members such as, for example, the doors of excavating shovels or scoops.

In the case of free swinging members such as the doors of excavating shovels and the like, it is frequently desirable to restrain free swinging movement of such members in order to prevent possible damage to the equipment and to personnel, and the principal object of the present invention is to provide a novel means for snubbing or damping free swinging movement of the hinged members which is highly efficient and effective in operation and use.

Another object of the invention is to provide snubbing or damping means as set forth which is of relatively simplified construction and comparatively inexpensive to manufacture.

A further object of the invention is to provide snubbing or damping means having the characteristics and advantages aforesaid which is positive in its action, is substantially foolproof and which is rugged and requires substantially no maintenance or up-keep.

These and other objects of the invention and the various features and details of the construction and operation thereof are hereinafter fully set forth and described with reference to the accompanying drawings, in which:

Fig. 1 is a side elevational view of a conventional type scoop or shovel customarily employed for excavating work;

Fig. 2 is a rear elevational view thereof;

Fig. 3 is an enlarged fragmentary view in side elevation of the snubber mechanism;

Fig. 4 is a rear elevational view of the disclosure in Fig. 3;

Fig. 5 is an enlarged sectional view on line 5—5, Fig. 4;

Fig. 6 is an enlarged sectional view on line 6—6, Fig. 4.

Referring now more particularly to the drawings, reference numeral 1 designates generally a scoop or shovel of the type usually employed on power shovels and like excavating equipment. The scoop or shovel 1 is supported by a bale 2 pivoted to the top thereof as indicated at 3, and a suitable door 4 is provided at the bottom of the shovel 1 for dumping the dirt or other material scooped into the shovel. In the illustrated embodiment of the invention the door 4 has upwardly curved arm portions 5 which are hinged or pivoted upon a rod or bar 6 that is carried by the shovel.

2

According to the present invention the arm portions 5 of the door 4 are each pivotally connected to suitable devices for snubbing or damping free swinging movement of the door 4 when it is unlatched to discharge the contents of the shovel. In the illustrated embodiment of the invention two snubbing devices are utilized but since they are identical only one of them need be described in detail. Thus, each door arm 5 is pivotally connected by a link 7 to the depending ear portions 8 of a bracket 9. The bracket 9 carries a pair of pins 10 arranged in spaced relation respectively adjacent the opposite ends of the bracket 9. As shown, these pins 10 project inwardly from the bracket 9 and have their projecting portions equally spaced at opposite sides of a vertically extending rib 11 secured to or forming a part of the rearward or back wall of the shovel.

Pivotedly mounted on the projecting end portion of these pins 10 are the lower end portions 12 of levers 13 which are pivotally mounted intermediate their ends upon other pins 14. The pins 14 are carried or mounted in relatively spaced ear portions 15 which are provided at the outer sides of brake shoes 16. These brake shoes 16 are faced with suitable friction material 17 and are disposed slidably within generally channel-shaped guides 18 which provide suitable brake surfaces 19 for engagement by the friction material 17. The guides are secured in back-to-back relation at opposite sides of the aforesaid vertically extending rib 11, for example, as shown in Figs. 5 and 6. Referring to Fig. 3 of the drawing, in order to insure against the brake shoes 16 locking or galling in their guides 18, it is desirable that the force imparted to the snubber by the links 7 upon initial opening of the door (represented by broken line F) pass a short distance below the center of the pins 14 on which the levers are pivoted.

The upper end portions 20 of the levers 13 curve upwardly and outwardly from their mounting pins 14, and their upper extremities are connected together by means of a rod 21 which has its opposite end portions threaded to receive nuts or other securing means 22. By this construction it will be observed that by adjusting the nuts 22 on the rod 21 the pressure of the brake shoes 16 and their frictional material 17 upon the brake surfaces of the guide members 18 may be increased or decreased as described thus increasing or decreasing the frictional resistance to sliding of the brake shoes 16 in the guide channels 18 consequently the snubbing or restraining action to free swinging movement of the door 4

upon its release to dump the contents of the scoop or shovel. Encircling the rod 21 and interposed and acting between the upper end portions 20 of the levers 13 is a coil spring 23 which, while not necessary to operation of the snubber, is desirable in order to smooth out the action that takes place and also to maintain the parts, such as the nuts 22, tight.

From the foregoing description it will be observed that the present invention provides novel means for snubbing or damping the free swinging movement of the hinged members which is highly efficient and effective in operation. The invention also provides novel snubbing or damping means which is positive in its action, is fool-proof and requires substantially no maintenance or up-keep. In addition, the device of the present invention is of relatively simplified construction and is comparatively inexpensive to manufacture.

While a particular embodiment of the present invention has been illustrated and described herein, it is not intended to limit the invention to such disclosure and changes and modifications may be made therein and thereto within the scope of the following claims.

We claim:

1. A snubber device for retarding free swinging movement of a hinged member, comprising fixedly mounted means having oppositely facing parallel brake surfaces extending normal to the hinge axis of the member, a bracket adjacent said brake surfaces and pivotally connected to the hinged member for actuation thereby in a direction longitudinally of said fixedly mounted means, brake shoes disposed in sliding engagement with said brake surfaces, levers pivotally mounted intermediate their ends on said brake shoes and having one end pivotally connected to said bracket, and means acting continuously on the other ends of the levers operable to maintain said brake shoes in predetermined constant pressure engagement with said brake surfaces.

2. A snubber device for retarding free swinging movement of a hinged member, comprising fixedly mounted means having oppositely facing parallel brake surfaces extending normal to the hinge axis of the member, a bracket adjacent said brake surfaces and pivotally connected to the hinged member for actuation thereby in a direction longitudinally of said fixedly mounted means, brake shoes disposed in sliding engagement with said brake surfaces, levers pivotally mounted intermediate their ends on said brake shoes and having one end pivotally connected to said bracket, an adjustable connection between the other ends of the levers, and means continuously acting on said other ends of the levers operable to maintain the brake shoes in predetermined constant pressure engagement with said brake surfaces, said means being adjustable to vary the contact pressure of the shoes on said surfaces to thereby regulate the snubbing action upon the hinged member.

3. A snubber device for retarding free swinging movement of a hinged member, comprising fixedly mounted means having oppositely facing parallel brake surfaces extending normal to the hinge axis of the member, a bracket adjacent said brake surfaces and pivotally connected to the hinged member for actuation thereby in a direction longitudinally of said fixedly mounted means, pins carried by said bracket and arranged respectively outwardly adjacent said brake surfaces, brake shoes disposed in sliding engagement

with said brake surfaces, levers pivotally mounted intermediate their ends on said brake shoes and having one end pivotally mounted on said pin, and means acting on other ends of the levers operable to maintain the brake shoes in predetermined constant pressure engagement with said brake surfaces.

4. A snubber device for retarding free swinging movement of a hinged member, comprising fixedly mounted means providing a plurality of parallel plane brake surfaces, a bracket adjacent said brake surfaces, means carried by the hinged member for actuating said bracket lengthwise of the brake surfaces, a brake shoe disposed in sliding engagement with each brake surface, levers carried by said bracket connected respectively to one of said brake shoes, and means acting continuously on said levers operable to maintain the brake shoes in predetermined constant pressure engagement with said brake surfaces.

5. A snubber device for retarding free swinging movement of a hinged member, comprising fixedly mounted means providing a plurality of parallel plane brake surfaces, a bracket adjacent said brake surfaces, means carried by the hinged member for actuating said bracket lengthwise of the brake surfaces, pins carried by said bracket, a brake shoe disposed in sliding engagement with each brake surface, levers carried by each pin and connected to one of said brake shoes, and means acting continuously on said levers operable to maintain the brake shoes in predetermined constant pressure contact with said brake surfaces.

6. In a snubber device for the hinged doors of excavating shovels, guide members secured upon the shovel and providing parallel brake surfaces extending normal to the hinge axis of the door, a bracket positioned crosswise of said brake surfaces and pivotally connected to the door for actuation thereby in a direction longitudinally of the brake surfaces, brake shoes having friction material thereon disposed in sliding engagement with said brake surfaces, levers pivotally mounted intermediate their ends on said brake shoes and having their lower ends pivotally carried by said bracket and their upper ends projected outwardly from the shovel, and means acting continuously on said upper ends of the levers operable to maintain the brake shoes in predetermined constant pressure contact with said brake surfaces.

7. A snubber as claimed in claim 6 wherein the position of the bracket upon initial opening of the hinged door is angularly related to the pivotal mounting of each lever so that the line of force imparted by the bracket passes below the center of the pivotal mounting of the lever.

8. In a snubber device for hinged doors of excavating shovels, guide members secured upon the shovel and providing parallel brake surfaces extending normal to the hinge axis of the door, a bracket positioned crosswise of said brake surfaces and pivotally connected to the door for actuation thereby in a direction longitudinally of the brake surfaces, brake shoes having friction material thereon disposed in sliding engagement with said brake surfaces, levers pivotally mounted intermediate their ends on said brake shoes and having their lower ends pivotally carried by said bracket and their upper ends projected outwardly from the shovel, and adjustable connection between the upper ends of the levers operable to vary the contact pressure of the shoes on said surfaces to thereby regulate the snubbing action upon the hinged member.

the snubbing action upon the door, and a spring acting intermediate said lever upper ends in opposition to said connection.

9. A snubber as claimed in claim 8 wherein the position of the bracket upon initial opening of the hinged door is angularly related to the pivotal mounting of each lever so that the line of force imparted by the bracket passes below the center of the pivotal mounting of the lever.
